(57) **CLAIM**

I claim the ornamental design for a toaster, as shown and described.

DESCRIPTION

FIG. 1 is a front perspective view of a toaster showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion 9 in FIG. 1;

FIG. 10 is an enlarged view of the encircled portion 10 in FIG. 1;

FIG. 11 is an enlarged view of the encircled portion in FIG. 2;

FIG. 12 is an enlarged view of the encircled portion in FIG. 5;

FIG. 13 is an enlarged view of the encircled portion 13 in FIG. 8; and,

FIG. 14 is an enlarged view of the encircled portion 14 in FIG. 8.

The evenly-dashed broken lines in the figures depict portions of the toaster which form no part of the claimed design. The dot-dot-dash broken lines encircling portions of the claimed design that are illustrated in enlargements form no part of the claimed design.

1 Claim, 12 Drawing Sheets
